UNITED STATES PATENT OFFICE.

VALENTIN NYEZNICK, OF AKRON, OHIO.

HYGIENIC SHAVING-SOAP RECEPTACLE.

Application filed February 23, 1927. Serial No. 170,136.

This invention relates generally to soap receptacles, and has more particular reference to a novel type of hygienic soap receptacle.

The invention has for an object the provision of a hygienic soap receptacle which is of simple construction, thoroughly sanitary and which can be manufactured and sold at a reasonable cost.

For further comprehension of the invention and of the objects and advantages thereof of reference will be had to the following description and accompanying drawing, and to the appended claims in which the various novel features of the invention are more particularly set forth.

Referring to the drawing forming a material part of this disclosure:

Fig. 1 is a side view of a device constructed according to this invention.

Fig. 2 is a central vertical sectional view thereof, with the brush inserted in the spout.

Fig. 3 is a view similar to Fig. 2 but with the cover of the device removed.

Fig. 4 is a perspective view of the soap foaming and draining chamber used in the invention device.

Fig. 5 is an enlarged fragmentary sectional view illustrating a modified form of finger catch.

Fig. 6 is a view of the brush used in this invention, with the bristle element removed from the handle.

The reference numeral 10 indicates generally a container of any desirable shape, and formed from glass, china, or any other suitable material, and provided with a handle 11, and a side spout 12. The container 10 is formed near its top with a groove 13 which supports a nickel plated ring 14 which may be held against turning by pins 15 engaged in the side of the container, and finger catches 16 project from this ring 14. The container 10 is also formed with a ridge 17 adapted to support the ring 18 of a soap foaming and draining chamber formed with a lower ring 19 and a plurality of side ribs 20 secured between the rings. The ring 18 is split at several points, such as at 21, so that a split is alignable with each of the finger catches 16, and one side of each split is formed with a slot 22 so that upon turning the soap foaming and draining chamber in the proper direction, the finger catches 16 engage in the slots 22 locking the chamber in position.

The chamber may be removed by turning in the opposite direction, freeing the

slots from the catches, and then lifting the chamber out from the container 10.

A cover 23 with a handle 24 may be used to cover the container 10 and a hingedly mounted sub-cover 25 on cover 23, may be used to cover the spout 12. A brush member 26 threadedly engageable in a handle 27 is used in connection with the device.

The modification illustrated in Fig. 5 shows the use of a catch finger 16' pivotally attached to the ring 14. A stop 28 is integral with the ring 14, and an adjusting screw 29 is engaged in the stop. A spring 30 is fastened at one end to the ring 14, and the other end of the spring acts against the catch finger 16' pressing the finger against the adjusting screw 29, which may be set so that the catch finger is engageable in the slot 22. This adjusting feature may be useful in cases where different foaming and draining chambers are used, and the slots 22 in these chambers are at slightly different heights.

Liquid soap 31 may be stored in the container 10, though the invention is not limited to the specific use of liquid soap. Normally the cover 23 is on the container 10 and the sub-cover 25 is over the spout 12, as shown in Fig. 1. In operation of the invention device, the covers are removed, and brush 26 held by handle 27 is inserted through the spout 12 into the container, and in the liquid soap 31. The soap wetted brush is then removed from the container, and briskly rubbed in a circular motion against the ribs 20 of the foaming and draining chamber. Naturally foam is produced in the chamber, while a portion of the liquid soap and a certain moist portion of the foam flows downward on the ribs and gathers in the container 10, thus eliminating waste. The soap foam may be applied to a person's face for shaving purposes.

While I have illustrated and described my invention with some degree of particularity, I realize that in practice various alterations therein may be made. I therefore reserve the right and privilege of changing the details of construction or altering the arrangement of the correlated parts without departing from the spirit or the scope of the appended claims.

Having thus described my invention, what I claim as new and desire to secure by United States Letters Patent is:

1. A hygienic soap receptacle comprising a container with a spout communicating

with the interior thereof for the application of a brush and formed with a groove near the top end, a ring secured in the groove, finger catches projecting from the ring, a ridge in the container, a draining and foaming chamber with a ring engageable on the ridge, and the latter mentioned ring being formed with slots engageable by the finger catches to hold the chamber in place.

2. In a hygienic shaving soap receptacle, the combination with a container, of a ring secured in said container near the upper open end thereof, finger catches projecting from said ring, and a foaming and draining member disposed in said container comprising a ring having splits and slots therein adapted to receive said finger catches when said foaming and draining member is moved relative to said container in a predetermined direction for removably retaining said foaming and draining member in place.

3. In a hygienic shaving soap receptacle, the combination with a container, of a ring secured in said container, finger catches pivotally mounted on said ring, an extension on said ring having threaded apertures therein, a set screw screwthreaded in said aperture and adapted to engage said pivotally mounted finger catches for adjustably positioning the same, and a foaming and draining member disposed in said container comprising a ring having splits and slots therein adapted to receive said adjustable finger catches for holding said foaming and draining member in place in said container.

4. A hygienic shaving soap receptacle of the class described comprising a container

having a groove around the upper open extremity thereof, a ring disposed in said groove, fingers mounted on said ring comprising a downwardly disposed section and a horizontally disposed extension, and a foaming and draining member disposed in said container comprising spaced apart ring sections having slots in the extremities thereof adapted to receive the horizontally disposed extension of said fingers for removably attaching said foaming and draining member to said first mentioned ring, the downwardly disposed portion of said fingers being accommodated in the space between said ring sections.

5. A foaming and draining device for shaving soap receptacles comprising a ring capable of being secured in the shaving soap receptacles, fingers on said ring, and a wire cage capable of being disposed in said receptacles comprising an upper split ring having slots therein adapted to receive said fingers, the said fingers being engaged in the said slots, a lower ring and spaced ribs attached at one end to said upper split ring at the other end to said lower ring.

6. A foaming and draining device for shaving soap receptacles comprising a ring adapted to be secured in a groove of a receptacle, fingers on said ring, and a wire cage member removably attached to said fingers comprising a ring having slots therein adapted to receive said fingers.

In testimony whereof I have affixed my signature.

VALENTIN NYEZNICK.
